INVENTOR

Fredric Oscar Thompson,
By his attorney,
Robert Cushman.

UNITED STATES PATENT OFFICE.

FREDERICK OSCAR THOMPSON, OF BROCKTON, MASSACHUSETTS.

LOCK FOR HINGED SHOE-LASTS.

SPECIFICATION forming part of Letters Patent No. 638,297, dated December 5, 1899.

Application filed March 18, 1899. Serial No. 709,574. (No model.)

To all whom it may concern:

Be it known that I, FREDERICK OSCAR THOMPSON, a citizen of the United States of America, and a resident of Brockton, county 5 of Plymouth, and Commonwealth of Massachusetts, have invented certain new and useful Improvements in Locks for Hinged Shoe-Lasts, of which the following is a specification.

My invention relates to hinged or break-down shoe-lasts. It is designed to hold a hinged shoe-last rigidly extended in its normal position while in use and at the same time to render it capable of being readily and instantly folded and shortened for the purpose 15 of withdrawing it from or inserting it in the shoe without danger of breaking or crippling the shank or the upper of the shoe. I attain these objects by the device illustrated in the accompanying drawings, in which—

20 Figure 1 is a vertical longitudinal section showing the position of my device while the last is extended and in its normal position and locked, and Fig. 2 is a vertical longitudinal section showing the position of my device 25 when the last is unlocked and folded.

The drawings show an ordinary hinged or folding shoe-last consisting of a fore part A and a heel part A', transversely separated at or near the shank, hinged together at B, and 30 having angularly-separating surfaces D and C on the fore and heel parts, respectively, above the hinge B and the usual jack-spindle socket K in the heel-section.

The bolt E in the angular space between the 35 separating-faces C and D of the heel and fore parts of the last constitutes the strut whereby the last is held extended. The strut E fits loosely at one end into the vertical slot or groove G in the separating-face C and bears 40 against the plate I, which forms the inner wall of the slot G. The slot G constitutes a socket for holding the end of the bolt E. The other end of the strut or bolt E is provided with a shoulder H, which when the strut is in 45 its lock position abuts against the washer-plate or lip-plate J about the mouth of the recess F, the tenon e extending into the recess F. The plate I is provided with a ledge i at its outer end, which engages the end of the

strut or bolt E when the latter is in its lock 50 position.

S is a coiled spring secured to the strut E near the end which bears upon plate I. The other end of spring S bears upon or is secured to the washer-plate J. Spring S performs the 55 double office of holding the end of the strut in its socket G and against plate I and forcing the last into its extended position. The plate I and washer-plate J serve as abutments which engage with the ends of the strut or bolt 60 E when the last is extended and the bolt is in its lock position. Another spiral spring S' is lodged in the pocket P, which is an extension of the slot or socket G and is attached at its outer end to the bolt E at a point between the 65 points of engagement I and J. Spring S' thus yieldingly holds the strut in engagement at both ends when the last is extended.

F is a recess in the fore part of the last for receiving the strut E, having its mouth in the 70 separating-surface D of the fore part. When the last is extended and the strut or bolt in the position shown in Fig. 1, the last is rigidly locked and capable of withstanding any 75 of the strains and pressures brought to bear upon it, the bolt preventing any pivotal motion of the sections.

The parts being constructed and arranged as shown, the operation of my improved last-lock is as follows: When it is desired to 80 shorten the last by the displacement of the sections, as shown in Fig. 2, for the purpose of removing the last from a shoe, the operator merely has to press on the bolt E, overcoming the stress of the spring S', so that the 85 shoulder H is thrown out of engagement with the washer-plate J. The heel part may then be folded up by a force sufficient to overcome the stress of spring S, bringing the surfaces C and D together, the bolt E disappearing 90 into the recess F, while its opposite abutting end acting as a movable pivot slips in the groove or socket G. When relieved of the force required to break and fold the last, spring S pushes the two sections of the last into their 95 extended position and at the same time pushes the bolt E out of the recess F. Spring S' at the same time automatically throws the strut

into its lock position, as shown in Fig. 1, with its ends in engagement with the ledge *i* and lip-plate *J*, respectively. In relasting a shoe—*i. e.*, in reinserting into a shoe a last that has 5 been previously withdrawn—the last is folded and shortened in the manner already described and the fore part is inserted in the corresponding part of the shoe, after which the heel-section is forced into its extended position, thus lengthening the last in the shoe, whereupon the spring *S* immediately throws the bolt *E* in its lock position. It will be seen that the automatic locking of the last is an important improvement in lasts of this 10 character over devices which require a separate motion to lock the last.

It is obvious that the lock may be reversed and the recess be in the heel part and the socket or slot for the pivot end of the strut in 20 the fore part of the last. I prefer to have the pivot end of the strut provided with two parallel faces to fit into the slot *G* to prevent the strut from turning and also to have the tenon on the shoulder end of the strut rectangular 25 and a rectangular mortise provided in the lip-plate *J* for receiving the tenon. It is obvious, however, that the same objects would be attained by providing a mortise or notch in the upper side of the recess *F* near its mouth 30 adapted to receive the end of the strut with or without a shoulder and tenon. When the last is not in use, it is desirable that its parts should be in their extended position and rigid, as there is less likelihood of the parts of the 35 last being broken or strained when the latter is moved about a factory than when the parts are permitted loosely to swing upon each other. This object is attained automatically and without any attention on the part of the operator 40 by the spring *S*, which throws the parts into their extended position, where they are automatically locked, as already described; but the chief function of spring *S* is to hold the pivot end of the bolt *E* in its socket and against 45 plate *I*.

The chief advantages of the particular structure which I have described as an embodiment of my invention are that it contains no articular parts or joints, thus rendering it 50 less expensive and less likely to get out of order than a structure containing articular parts or joints. Moreover, the bolt can be readily removed from the last by the hand, when desired, by simply throwing it out of its 55 lock position and compressing the spring *S*. On the other hand, it cannot come out of the last unless taken out; but the most important feature of my invention is the arrangement of the parts whereby the bolt is automatically urged toward and held in its lock position.

What I claim, and desire to secure by Letters Patent, is—

1. A shoe-last comprising a fore part and a heel part hinged together, a bolt between the 60 separating-faces of the fore part and heel part of the last, the bolt adapted to lock the sections of the last in extended position, and to

be moved from its lock position in response to the application of force, and means whereby the said bolt is normally urged toward and 70 held in its lock position, substantially as described.

2. A shoe-last comprising a fore part and a heel part hinged together, a bolt between the separating-faces of the fore part and heel part 75 of the last, the bolt adapted to lock the sections of the last in extended position, and to be moved from its lock position in response to the application of force, and means whereby the said bolt is normally urged toward and 80 held in its lock position, and means whereby the two parts of the last are normally urged into their extended position, substantially as described.

3. In a hinged shoe-last, the combination 85 with the hinged fore and heel portions of the last, of a bolt located between and abutting against the fore and heel portions of the last, a spring normally urging the said bolt toward and holding it in its lock position, the said 90 bolt adapted to be moved from its lock position by the application of force against the pressure of its spring, substantially as described.

4. In a hinged shoe-last, the combination 95 with the hinged fore and heel portions of the last, of a bolt located between and abutting against the fore and heel portion of the last, a spring normally urging the said bolt toward and holding it in its lock position, the said 100 bolt adapted to be moved from its lock position by the application of force against the pressure of its spring and means whereby the two parts of the last are normally urged into 105 their extended position, substantially as described.

5. In a hinged shoe-last, the combination with the hinged fore and heel parts of the last of a rigid bolt, abutments in the separating-surfaces of the heel and fore parts respectively, normally in engagement with the said bolt, a recess in one of the hinged portions of the last proportioned and adapted to receive the bolt which is movable from its abutments into engagement with the recess, 115 substantially as described.

6. In a hinged shoe-last, the combination with the hinged fore and heel parts of the last of a rigid bolt, abutments in the separating-surfaces of the heel and fore parts, respectively, normally in engagement with the said bolt, a recess in one of the hinged portions of the last proportioned and adapted to receive the bolt which is movable from its abutments into engagement with the recess, 120 125 means whereby the spreader is normally urged into engagement with its abutments, substantially as described.

7. In a hinged shoe-last, the combination 130 with the hinged fore and heel parts of the last of a rigid bolt, abutments in the separating-surfaces of the heel and fore parts, respectively, normally in engagement with the said bolt, a recess in one of the hinged por-

tions of the last proportioned and adapted to receive the bolt which is movable from its abutments into engagement with the recess, means whereby the bolt is normally urged 5 into engagement with its abutments and means whereby the separating-surfaces of the last are normally urged apart, substantially as described.

8. In a hinged shoe-last, the combination 10 with the hinged fore and heel parts of the last of a rigid bolt, a socket in one of the separating-faces of said parts in engagement with one end of the bolt, a recess in the other part of the last adapted to receive the bolt, a 15 plate across the mouth of said recess normally in engagement with the other end of said bolt; means for urging the bolt toward and yieldingly holding it in its lock position, means for holding one end of the bolt in engagement with the socket, substantially as described.

9. In a hinged shoe-last, the combination 20 with the hinged fore and heel parts of the last, of a rigid bolt, a socket in one of the separating-faces of said parts in engagement with one end of the bolt, a recess in the other part of the last adapted to receive the bolt, a 25 plate across the mouth of said recess nor-

mally in engagement with the other end of said bolt, means for urging the bolt toward 30 and yieldingly holding it in its lock position, means for urging one end of the bolt into engagement with the socket and the last into its extended position, substantially as described.

10. In a hinged shoe-last, the combination 35 with the hinged fore and heel parts of the last, of a rigid bolt, a vertical slot in one of the separating-faces of said last provided with a ledge at its outer end normally in engagement with one end of the bolt, a recess in the 40 other part of the last adapted to receive the bolt, a plate across the mouth of said recess normally in engagement with the other end of said bolt, means for urging one end of the bolt toward and holding it in said slot and at 45 the same time forcing the last into its extended position, means for urging the ends of the bolt toward and yieldingly holding them in engagement with said ledge and plate respectively, substantially as described. 50

Signed by me at Boston, Massachusetts, this 15th day of March, 1899.

FREDERICK OSCAR THOMPSON.
